(57) **CLAIM**

The ornamental design for an avionics display screen with computer icon, as shown and described.

DESCRIPTION

A portion of the disclosure of this patent document contains material subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view showing an avionics display screen with computer icon, showing our new design; and, FIG. 2 is a front view showing a second embodiment of our new design.

The outermost broken line showing of the display screen and all other broken lines showing portions of the graphical interface are included for the purpose of illustrating portions of the article and form no part of the claimed design.

The claimed “computer-generated frustum icon pair formed of icon elements and portion of an avionics display” is used as a visual instrument interface for assisting in spatial awareness.
